(57) **CLAIM**

I claim the ornamental design for an eye mask, as shown and described.

DESCRIPTION

FIG. 1 is a perspective view of an eye mask showing my new design;

FIG. 2 is a front view thereof;

FIG. 3 is a rear view thereof;

FIG. 4 is a side view thereof;

FIG. 5 is a side view opposite FIG. 4;

FIG. 6 is a top view thereof;

FIG. 7 is a bottom view thereof;

FIG. 8 is a perspective view thereof, the only difference is the addition of the headphones shown in broken lines;

FIG. 9 is a front view of FIG. 8;

FIG. 10 is a rear view of FIG. 8;

FIG. 11 is a side view of FIG. 8;

FIG. 12 is a side view of the opposite side of FIG. 11;

FIG. 13 is a top view of FIG. 8; and,

FIG. 14 is a bottom view of FIG. 8.

The broken lines are illustrative of environmental structure only and form no part of the claimed design.
